Emanuel J. Perry, New Bedford, Mass.

Application October 2, 1939, Serial No. 297,614

15 Claims. (Cl. 68—20)

This invention relates to improvements in apparatus for subjecting clothes or other articles to the various operations of washing, extracting, tumbling and drying or dry-cleaning operations.

It has been the practice heretofore to handle clothes and other articles many times during the laundering or cleaning process, subjecting these articles to excessive wear, high labor cost, and necessitating availability of a considerable amount of floor space and a relatively great length of time to complete the washing or cleaning cycles. Ordinarily the articles are placed in a washing machine and therein subjected to the action of water and a detergent or cleaning solvent, after which the articles are transferred to an extractor where the liquids are removed and thereafter placed in a tumbler to be shaken out and dried.

My invention contemplates for its general object the provision of a unitary device which will accomplish all or any selected of the various functions of washing, extracting, tumbling and drying, thus eliminating any need for separate machines and the transfer of articles to and from various containers and, in general, an improved device for washing or cleaning and drying clothes or other articles.

Another object is to provide a device of the above character having clothes containers rotatable or oscillatable about different axes such as the vertical and horizontal and which does not require mechanism for tilting or otherwise altering the position of the containers in the casing.

Another object is to provide a novel and improved apparatus for centrifugally extracting liquid from the washed articles whereby the articles are less susceptible to injury during this operation.

A further object contemplates the provision of a novel and more efficient arrangement of parts for introducing drying air into the machine during the drying operation.

A still further object is to provide a novel arrangement of a plurality of clothes containers, each of which may be operable to effect the various operations and possesses the various advantages above described.

Other objects and advantages of the invention will be apparent from the following description taken in conjunction with the accompanying drawings wherein preferred embodiments of the principles of the invention have been selected for exemplification.

Figure 1 is a plan view of a machine embodying the form of the present invention.

Figure 2 is a vertical sectional view taken on the lines 2—2 of Figure 1.

Figure 3 is a vertical sectional view taken on the line 3—3 of Figure 1.

5 Figure 4 is an enlarged fragmentary sectional view showing operating parts for rotating or oscillating the clothes containers of Figures 1, 2 and 3 on a horizontal axis.

10 Figure 5 is a diagrammatic illustration of a suggested electrical hook-up for the form of the invention shown in Figures 1—4.

Figure 6 is a side elevational view partly broken away of a machine embracing another form of the present invention.

15 Figure 7 is a vertical sectional view taken on the line 7—7 of Figure 6.

Referring more particularly to the drawings, wherein like numerals refer to like parts, an outer casing indicated generally at 10 includes a 20 bottom wall 12, side walls 14 and a top 16 and is provided with a door 6. Side supports 18 may be provided for anchoring the casing to a floor or other suitable foundation.

Extending centrally and vertically of the casing 25 10 is a shaft 20, rotatably supported at its lower end and in bearing 22 provided at the bottom 12 of the casing at its upper end in a bearing 24 at the top 16 of the casing. The shaft 20 intermediate its ends has welded or otherwise secured thereto a housing 26 in which bearings 28 are provided for rotatably receiving a horizontally extending stub shaft 30, to the outer ends of which are secured perforated containers 32 and 33. A nut or the like 34 may be threaded to 30 the extremities of the stub shaft 30 projecting inside the containers to hold the containers 32 and 33 integral with the stub shaft for rotation on a common horizontal axis. The containers 32 and 33 may be of the conventional type with ribs 35 or other baffle means for tumbling or agitating the articles during washing and each has a suitable door 8 for loading or unloading. The outer walls of the cylinders 32 and 33 may be rounded to correspond generally with the interior curvature of the side walls 14 of the casing 10.

40 A pulley 34 keyed to upper extending portion of the shaft 20 is connected with belts 36 or other suitable means to the drive shaft 37 of an electric motor 38. Guard plate 40 may house 45 the shaft 37, belts 36 and pulley 34 which rotate the shaft 20 which in turn rotates the containers 32 and 33 supported by stub shaft 30 about the vertical axis of the shaft 20 for extracting liquid from the containers. Extractors 50 commonly are rotated on an axis extending through

the container with the result that garments or other articles in the center of the container are subjected to opposed forces and often spread apart and torn. This is obviated in the present manner of extracting wherein the containers are rotated in the casing or tub around an axis offset from the bodies of the containers and the articles contained therein are subjected to centrifugal force in one direction only.

For rotating the containers 32 and 33 about their common horizontal axis a sliding shaft 42 extends through a side wall of the casing 10 and is disposed axially of the opposed cylinders 32. A thrust collar 44 is keyed to the shaft 42 and a lever 46 is connected to the collar 44 and fulcrumed relative to the casing at 48 to effect sliding movement of shaft 42 in a direction inwardly and outwardly of the casing and into and out of engagement with a spline casting 50 mounted centrally of the outer wall of container 33 meshing with spline end 52 of shaft 42.

A wide gear 54 is keyed to the shaft 42 meshing with narrow gear 56 when the shaft 42 is in either its innermost or outermost position. The gear 56 is mounted on a counter shaft 58 to which is fastened a pulley 60 connected by belts 62 or the like to the drive shaft 64 of an electric motor 66.

Through the medium of an interlock, the operation of which is hereinafter explained, the shaft 42 is prevented from being shifted inwardly of the casing while the vertical shaft 20 is in motion, and through another means hereafter described application of power to the shaft 20 is prevented when sliding shaft 42 is in driving engagement with the spline 50 of container 33.

The motors 38 and 66 may be three phase induction motors and a suggested electrical circuit is diagrammatically illustrated in Figure 5 wherein a jog control 68 for selectively positioning the containers within the casing is provided for rotating vertical shaft 20 in addition to the usual start and stop controls 70 and 72. Current may be supplied to the motor 38 for rotating the shaft 20 through conductors 74, 75 and 76 and a contactor or magnetic switch 77 having an operating coil 78.

The motor 38 for driving the shaft 20 may be started by depressing the start button 70 to energize the operating coil 78 of the contactor 77 to close the contacts thereof including contacts 79. The circuit through the operating coil 78 may be traced from conductor 74 through conductor 80, the contacts of starting button 70, conductor 81, conductor 82, contacts of a cut-out switch 83, conductor 84, contacts of the stop button 72, and operating coil 78 to conductor 75. It will be seen that the switch 83 is opened by movement of lever 46 which shifts shaft 42 into driving relation with container 33. Thus, it is impossible to start the motor 38 when the shaft 42 is engaged.

Closing of the contactor 77 sets up a holding circuit to maintain the contactor closed when the start button is released. This circuit may be traced from conductor 74 through closed contact 79 of the contactor 77, conductor 85, upper normally closed contacts of jog button 68, conductor 86, conductor 81, conductor 82, switch 83, conductor 84, contacts of stop button 72, and operating coil 78 to conductor 75. It will be noted that the contacts of the stop button 72 are included in the circuit just traced, so that depression of the stop button is effective to deenergize the operating coil 78 of the contactor 77 and stop the motor 38. The jog button 68 has its lower

contacts in parallel with the contacts of the starting button 70, so that depression of the jog button also starts the motor 38. However, the upper contacts of the jog button are in series with the holding circuit above traced so that the contactor 77 opens before the jog button returns to close its upper contacts after this button has been depressed. Thus, depression of the jog button when the motor is stopped causes the motor to 10 run only while the jog button is depressed.

The shaft 42 is provided with a collar 87 which is engaged by a latch 88 to prevent shifting of the shaft 42 when the shaft 20 is rotating. When the shaft 20 is stationary, the latch 88 is raised by 15 a solenoid 89 so that shaft 42 can be shifted. The energization of the solenoid 89 is accomplished through a mercury switch 90 carried by the upper end of shaft 20 and arranged so that the mercury therein is thrown away from the contacts 91 by centrifugal force when the shaft 20 rotates. Upon stopping of shaft 20, the mercury completes the circuit across the contacts 91 to 20 energize the solenoid 89 and release the latch 88.

The motor 66 for driving the shaft 42 may be 25 connected to its source of power through a contactor 92 provided with an operating coil 93. Stop, start and jog buttons 94, 95 and 96 are likewise provided for the motor 66. The control circuit including the buttons 94, 95 and 96 and the operating coil 93 is entirely similar to the control circuit for the motor 38, except that no cut-out switch 83 is necessary. This circuit need not be further described, as its operation will be apparent from the above description of the circuit involving control buttons 68, 70 and 72 and operating coil 78 for the contactor 77. The motor 66 is ordinarily further controlled to make a plurality of revolutions in one direction and then a plurality of revolutions in the reverse direction 30 so as to cause rotation of the containers 32 and 33 about their horizontal axis alternately in opposite directions through several revolutions in order to prevent balling of the clothes in the containers. Such a reversing mechanism is indicated at 97. As the details of such reversing mechanisms are known to the prior art, they need 35 not be further described.

Water, solvent or other washing material is 40 fed into the casing 10 through a pipe 100 having a control valve 102. Spent washing fluid may be drained from the casing through a discharge line 104 communicating with the bottom of the casing and controlled by the valve 106. A sight glass 108 45 may be provided in the line 104 to visually determine the condition of the outgoing fluid.

Drying air to be passed to the casing 10 may be 50 drawn through a series of steam heated coils 110 by a fan 112 connected directly to a motor 114 and the heated air passed through a duct 116 communicating with a lower portion of the casing 10. A conical shaped sheet 118 is provided in the 55 lower portion of the casing 10 and welded or otherwise secured to the bottom and side walls 12 and 14, respectively, to form a circular duct 120 surrounding the lower liquid holding or tub portion of the casing 10 and in communication with air inlet duct 116. Short ducts 122 provided along the side walls 14 of the casing connect lower duct 120 with the interior of the casing and are so disposed as to direct drying air into the cylinders 32 and 33 through the perforated end walls thereof at their centers, that is to say, in a direction 60 axially of the horizontally rotating containers. This particular arrangement has been found to 65

be of considerable advantage in that a maximum of drying air is passed through the cylinders to dry the clothes or other articles therein before the air is vented through outlet 124.

In the operation of the device above described, jog button 96 may be used to effect positioning of the containers 32 and 33 in the casing 10 so that the doors 8 thereof are brought into alignment with doors 6 provided in the outer wall of the casing 10 and clothes or other articles to be washed or cleaned are deposited in either or both containers 32 and 33. Lever 46 may then be operated to force shaft 42 inwardly to mesh the splined end 52 thereof with splined casting 50 mounted centrally of the outer wall of container 33. The circuit to motor 66 may then be closed at the starter button 95 to rotate shaft 42 through belt 60, countershaft 58 and gears 54 and 56 whereby the container 33 and container 32 connected thereto by the stub shaft 30 may be rotated on a substantially horizontal axis to wash or tumble the articles contained therein in the cleaning fluid which has been passed to the casing 10 through the inlet pipe 100. If desired, the reversing mechanism 97 may be availed of to effect periodic rotation of the containers in opposite directions instead of continuous rotation in the same direction.

After a suitable interval, when the washing or cleaning operation is completed, the circuit through motor 66 may be broken by operation of the stop switch 94 and the lever 46 operated to shift the shaft 42 outwardly of the casing to bring the splines 52 and 50 out of mesh. When the lever 46 is in disengaged position, the cut-out switch 83 will be closed to enable the motor 38 to be started. After the spent washing fluid has been drained from the casing through the line 104, the motor 38 may be started by depressing the starter button 10 and the shaft 20 rotatably driven through the motor drive 37, belts 36, and pulley 34, so that the containers 32 and 33 may be rapidly rotated about the axis of the shaft 20 whereby washing fluid entrained with the clothes or other articles may be centrifugally extracted from the containers. Good results may be obtained for ordinary purposes by rotating the shaft 20 during the extraction operation at about 400 R. P. M., while 20 R. P. M. is usually sufficient for rotation of the containers on their horizontal axis during the washing operation.

Upon completion of the extraction operation, the containers 32 and 33 may be horizontally rotated as above described and the motor 114 energized to draw air through the steam coils 110 or other means and force the same through the duct 116 into the duct 120 surrounding the liquid holding portion of the casing through the short ducts 122 and into the containers 32 and 33 axially of the ends thereof. In this manner the drying air may be most efficiently utilized to directly contact the articles tumbling in the containers to thoroughly dry the same, the spent drying air being removed through the vent 124. The containers may then be jogged into position whereby the doors 8 thereof are in alignment with the casing door 6 and the washed and dried articles withdrawn therefrom.

The form of the invention illustrated in Figures 6 and 7 employs the general principles characterizing the above described form but makes possible the use of a single power source for effecting both horizontal and vertical rotation of the containers.

Herein, an outer casing identified generally by 126 is provided with a bottom wall 128, side walls 130 and a top 132. A skirt or the like 134 may be provided for securing the casing to a floor or other support. A shield or housing 136 is disposed substantially centrally and vertically of the casing 126 and rotatably secured therein at its lower end 139 by a bearing 138 disposed outside of the bottom wall 128 of the casing free of the washing fluid and supported at its upper end by a bearing 140. A stub shaft 142 projects horizontally beyond an intermediate portion of the shield 136 and is supported thereby for rotation on a horizontal axis by bearing 144 secured to the shield. Secured to the outer ends of the stub shaft 142 for horizontal rotation therewith are containers 146 and 147, each having suitable doors 148, the containers 146 and 147 being generally similar in structure to the containers 32 and 33 and similar in operation in that they are supported for concurrent horizontal rotation independently of the shield 136 and rotatable about the vertical axis of the shield 136.

A large sprocket wheel 150 is keyed to the stub shaft 142 and positioned entirely within the support or housing 136 to be shielded from the washing fluid. Freely rotatable guide sprockets 152 supported by brackets depending from the top of the member 136 mesh with sprocket chain 154 connecting driven sprocket 150 to a drive sprocket 156 rotatable on a shaft 158 which passes through an extension of the shield 136 exteriorly of the casing 126. Integral with the sprocket 156 is a bevel gear 160 meshing with another bevel gear 162 secured centrally of a disc 164 rotatably supported in a housing 166 on the top wall 132 of the casing 126. Disc 164 is driven by belts or the like 168 connected to drive shaft 170 of a suitable electric motor or the like (not illustrated). An expanding clutch 172 operable by any conventional means is carried by a plate secured to the shaft 158 and comprises a means for selectively frictionally engaging the shield 136 and containers 146 and 147 carried thereby with the disc 164 for rotation therewith. A brake drum 174 and an associated brake band 175 is secured to an upper extending portion of the member 136 adjacent the disc 164 and rotates with the member 136 and the above mentioned gears and sprocket connections when the clutch 172 is in operative engagement with disc 164.

To rotate the containers 146 and 147 on their common horizontal axis, the brake drum band 175 operated by any convenient means (not shown) will brake the drum 174 to hold shield 136 and disengaged clutch 172 stationary. Thereupon rotation of the disc 164 through bevel gears 162 and 160 and sprocket 156 will drive sprocket chain 154 to rotate stub shaft 142 and containers 146 and 147 carried thereby.

In this form of the invention provision is also made for directing drying air axially of the containers 146 and 147 through ducts 178 and 180 extending through the side wall of the casing 126, the air being exhausted through an outlet 182. Washing liquid or the like charged to the casing may be drained through an outlet 184 at the bottom of the casing.

It will be apparent that the operation of the modified form of the invention is similar in its essentials to the first described form, a structural advantage residing in the fact that a single driving means is employed for effecting horizontal rotation of the containers 146 and 147 for washing and drying and rotation or spinning about

an axis extending centrally of the casing and offset from the containers during the extraction operation.

It will be understood that the forms of the invention herein illustrated and described are exemplary only of the broad principles of the invention as defined in the following claims.

What I claim is:

1. A washing and extracting and drying machine comprising a cleaning fluid holding casing, a perforated container supported within said casing for rotary movement on an axis extending through the container, means for rotating the container on said axis for tumbling the contents of said container in said cleaning fluid, the said container being also supported within said casing for independent rotation on a second axis offset from said container, and means for rotating said container at a high speed about said second axis to extract cleaning fluid from the contents of said container.

2. A washing and extracting and drying machine comprising a cleaning fluid holding casing, a plurality of containers supported within said casing each for rotary movement on a substantially horizontal axis, means for imparting rotary movement to one of said containers on said substantially horizontal axis for tumbling the contents of said one container in the cleaning fluid, the said containers being also supported within said casing for rotation around a substantially vertical axis offset from the containers independently of said substantially horizontal rotation, and means for rotating said containers at a high speed about said substantially vertical axis to extract cleaning fluid from the contents of said containers.

3. A washing and extracting machine comprising a cleaning fluid holding casing, a rotatable support disposed substantially centrally and vertically of said casing, a perforated container, means securing said container to one side of said central support for rotary movement on a substantially horizontal axis extending through the container and for rotary movement with said central support around the offset axis of said central support, means for rotating said container on said substantially horizontal axis for tumbling contents of the container in said cleaning fluid, and means for rotating said container at a high speed around the vertical axis of said central support for extracting cleaning fluid from the contents of said container.

4. A washing and extracting machine comprising a cleaning fluid holding casing, a rotatable support disposed substantially vertically of said casing, a plurality of perforated containers, means securing said containers to said vertical support, each for rotary movement on a substantially horizontal axis extending through the container and each for rotary movement with said vertical support around the axis of said vertical support, means for simultaneously rotating each of said containers on its substantially horizontal axis for tumbling contents of the containers in said cleaning fluid, and means for rotating said containers at a high speed around the axis of said vertical support for extracting cleaning fluid from the contents of said containers.

5. A washing and extracting machine comprising a cleaning fluid holding casing, a rotatable support disposed substantially vertically and centrally of said casing, a pair of perforated cylindrical containers, means securing said containers to said vertical support in axial alignment

for rotary movement on a common substantially horizontal axis extending through each container and for rotary movement with said vertical support around the axis of said vertical support, means for rotating said containers on their substantially horizontal axis for tumbling contents of the containers in said cleaning fluid, and means for rotating said containers at a high speed around the vertical axis of said central support for extracting cleaning fluid from the contents of said container.

6. A washing and extracting machine comprising a cleaning fluid holding casing, a rotatable support disposed substantially vertically and centrally of said casing, a shaft rotatably carried by and extending outwardly of opposed sides of said vertical support, a pair of perforated cylindrical containers, one each secured to an extended end of said shaft and each in axial alignment with said shaft, means for rotating said containers on the axis of said shaft for tumbling contents of the containers in said cleaning fluid, and means for rotating said containers at high speed around the axis of said vertical support for extracting cleaning fluid from the contents of said containers.

7. A washing and extracting machine comprising a cleaning fluid holding casing, a vertically extending shaft rotatably supported substantially centrally of said casing, an anti-friction bearing member carried by said vertical shaft, a horizontally extending stub shaft supported in said bearing member for rotation with said vertical shaft and for rotation on its horizontal axis independently of said vertical shaft, a pair of perforated cylindrical containers one each secured to an extended end of said stub shaft, the said containers and said stub shaft being in axial alignment and secured together for common rotation on a horizontal axis, means including a drive shaft projectable inside said casing into axial engagement with one of said containers whereby said containers are rotated to tumble the contents thereof in said cleaning fluid, and means for rotating said vertical shaft and said containers carried thereby at high speed whereby to extract cleaning fluid from the contents of said containers.

8. A washing and extracting machine comprising a cleaning fluid holding casing, a rotatable support disposed substantially centrally of said casing, a perforated container, means securing said container to one side of said central support for rotary movement on a substantially horizontal axis extending through the container and for rotary movement with said central support around the offset axis of said central support, means for rotating said container on said substantially horizontal axis for tumbling contents of the container in said cleaning fluid, means for rotating said container at a high speed around the axis of said central support for extracting cleaning fluid from the contents of said container, and a conduit for introducing drying air substantially horizontally into said casing at the height of said horizontal axis, said cylindrical container being adapted to be positioned in axial alignment with said conduit whereby drying air is directed axially into the container.

9. A washing and extracting machine comprising a cleaning fluid holding casing, a rotatable support disposed substantially vertically and centrally of said casing, a shaft rotatably carried by and extending outwardly of opposed sides of said vertical support, a pair of perforated cylind-

drical containers, one each secured to an extended end of said shaft and each in axial alignment with said shaft, means for rotating said containers on the axis of said shaft for tumbling contents of the containers in said cleaning fluid, means for rotating said containers at high speed around the axis of said vertical support for extracting cleaning fluid from the contents of said containers, and conduits for introducing drying air into opposite sides of said casing, said containers being adapted to be positioned in axial alignment with said conduits whereby drying air is directed axially into each of said containers.

10. A washing and extracting machine comprising a cleaning fluid holding casing, a rotatable hollow support disposed substantially centrally of said casing, a perforated container, means securing said container to one side of said central support for rotary movement on an axis extending through the container and for rotary movement with said central support around the offset axis of said central support, means including drive means extending through said hollow support for rotating said container on said axis extending through the container for tumbling contents of the container in said cleaning fluid, and means for rotating said container at a high speed around the axis of said central support for extracting cleaning fluid from the contents of said container.

11. A washing and extracting machine comprising a cleaning fluid holding casing, a rotatable hollow support disposed substantially vertically and centrally of said casing, a shaft rotatably carried by and extending outwardly of opposed sides of said vertical support, a pair of perforated cylindrical containers, one each secured to an extended end of said shaft and each in axial alignment with said shaft, means including drive means extending through said hollow support for rotating said containers on the axis of said shaft for tumbling contents of the containers in said cleaning fluid, and means for rotating said containers at high speed around the axis of said vertical support for extracting cleaning fluid from the contents of said containers.

12. A washing, extracting and drying machine comprising a cleaning fluid holding casing, a rotatable hollow support disposed substantially centrally of said casing, a perforated container, means securing said container to one side of said central support for rotary movement on an axis extending through the container and for rotary movement with said central support around the offset axis of said central support, means including drive means extending through said hollow support for rotating said container on said axis extending through the container for tumbling contents of the container in said cleaning fluid, means for rotating said container at a high speed around the axis of said central support for extracting cleaning fluid from the contents of said container, and a conduit for introducing drying air substantially horizontally into the casing at

the height of said horizontal axis, said container being adapted to be positioned relative to said conduit so that drying air is directed into said container axially of its horizontal rotational axis.

13. A washing and extracting and drying machine comprising a cleaning fluid holding casing, a perforated container supported within said casing for rotary movement on an axis extending through the container, means for rotating the container on said axis for tumbling the contents of said container in said cleaning fluid, the said container being also supported within said casing for independent rotation on a second axis offset from said container, and means for rotating said container at a high speed about said second axis to extract cleaning fluid from the contents of said container, and a conduit communicating with said casing for introducing drying air, said container being adapted to be positioned relative to said conduit so that drying air is directed into said container axially of the rotational axis extending through said container.

14. A washing and extracting and drying machine comprising a cleaning fluid holding casing, a plurality of containers supported within said casing each for rotary movement on a horizontal axis, means for imparting rotary movement to one of said containers on said horizontal axis for tumbling the contents of said one container in the cleaning fluid, the said containers being also supported within said casing for rotation around a vertical axis offset from the containers independently of said horizontal rotation, and means for rotating said containers at a high speed about said vertical axis to extract cleaning fluid from the contents of said containers, and a conduit for introducing drying air into said casing at the height of said horizontal axis, said containers being adapted to be positioned in alignment with said conduit whereby drying air is directed into said containers along said horizontal axis of rotation of the containers.

15. A washing and extracting machine comprising a cleaning fluid holding casing, a rotatable hollow support disposed substantially vertically and centrally of said casing, a shaft rotatably carried by and extending outwardly of opposed sides of said vertical support, a pair of perforated cylindrical containers, one each secured to an extended end of said shaft and each in axial alignment with said shaft, means including drive means extending through said hollow support for rotating said containers on the axis of said shaft for tumbling contents of the containers in said cleaning fluid, means for rotating said containers at high speed around the axis of said vertical support for extracting cleaning fluid from the contents of said containers, and conduits for introducing drying air into opposite sides of said casing, said containers being adapted to be positioned in axial alignment with said conduits whereby drying air is directed axially into each of said containers.

EMANUEL J. PERRY.
